ENVELOPE

Joseph A. Russo, Pittsburgh, Pa.

Application October 14, 1949, Serial No. 121,289

5 Claims. (Cl. 229—85)

1

This invention relates to envelopes used primarily for mailing purposes, and more particularly, to a novel envelope having means for quickly and easily opening same and extracting the enclosed letters or other contents without any possibility of tearing or mutilating the contents.

Briefly described, the specific embodiment of the invention disclosed herein for purposes of illustration comprises an envelope having a string disposed along one edge for tearing the latter open when pulled, an extractor loop adapted to surround and engage the contents of the envelope so as to extract the contents of the envelope when the loop is drawn outwardly, guide means to mount said extractor loop for rectilinear sliding movement, and tear string means for automatically severing said loop when the latter reaches a predetermined outward position so as to enable the contents to be readily dissociated from the loop after extraction.

A primary object of the present invention is to provide an envelope which may be quickly and easily opened and emptied without any possibility of tearing or mutilating the enclosed contents.

Another object is to provide a novel extractor means for engaging the contents of the envelope and for extracting the contents when moved outwardly.

A further object of the invention is to provide a novel means for slidably mounting said extractor means for guided rectilinear movement as said means and contents are pulled outwardly from the envelope.

Another and important object of the present invention is to provide a construction whereby the extractor will be automatically disengaged from the contents when said means and said contents have been drawn outwardly from the envelope, whereby the extractor means may be readily dissociated from the contents after extraction.

Other objects and advantages are either inherent in the invention as claimed and disclosed or will be readily apparent from both the detailed description hereinbelow and the drawings wherein is described and illustrated a preferred embodiment of the invention. It is to be understood that the scope of the invention is delineated in the appended claims, the specific embodiment shown and described being merely an exemplification.

In the drawings:

Figures 1, 2 and 3 are perspective views show-

2

ing the manner and sequence of operations in opening the envelope and extracting the contents therefrom;

Figure 4 is a rear face view of the envelope with the rear face partially broken away;

Figure 5 is a longitudinal sectional view of one end of the envelope showing the tear string drawn taut and about to sever the extractor loop;

Figure 6 is a transverse sectional view taken substantially on the line 6—6 of Figure 4;

Figure 7 is a horizontal longitudinal sectional view taken on the line 7—7 of Figure 4;

Figure 8 shows the pattern or blank from which the envelope is formed;

Figure 9 is a perspective detail view of the extractor loop;

Figure 10 is a sectional view of the rear end portion of the extractor loop taken on the line 10—10 of Figure 9 and showing the tear string attached to the weakened portion of the loop; and

Figure 11 is an exploded perspective view showing the details of construction of the rear end portion of the extractor loop.

Referring to the drawings and in particular to Figure 8, the pattern or blank from which the envelope is formed is indicated generally by the reference numeral 15. Blank 15 comprises a front wall portion 16 and a flap or rear wall portion 17 joined to the portion 16 at the fold-line 18. Flap portions 19 and 20 extend laterally from the front wall portion 16 and are joined thereto at fold-lines 21 and 22 respectively. At the top of the front wall portion 16 is a sealing flap 23 provided with adhesive indicated at 24.

It is obvious that the blank or pattern 15 may be folded and sealed to form an envelope by folding the rear wall portion 17 upwardly and then folding the laterally extending flap portions 19, 20 inwardly over the rear wall portion 17.

Referring now to Figure 9, there is shown a means for extracting the contents of the envelope, said extracting means being in the form of an extractor loop indicated generally by the reference numeral 25. The extractor loop 25 comprises an elongated U-shaped member 26. As shown in Figure 11, each of the ends of the legs of the elongated U-shaped member 26 has integral therewith a relatively wide portion 27 having a flap 28 and a slit 29 extending in a direction parallel to the elongated legs of U-shaped member 26. It will be noted that only the end of one of the elongated legs of member 26 is shown in Figure 11, the end of the other leg being identical therewith. The reference numeral 30

indicates a member adapted to be secured to portion 27 and to be slidably mounted therewith, the member 30 comprising a triangular-shaped portion 31 and two flanges 32, 33 extending from the apex of said portion 31. The reference numeral 34 indicates generally a weakened strip or loop portion adapted to be easily severed when the extractor loop 25 reaches a predetermined position outwardly of the envelope. It will be noted that in Figure 11, the weakened loop portion 34 is partially broken away, the remainder being of the same shape as the part shown. The weakened loop portion 34 is tapered as at 35 and 36 so as to form a relative narrow section at the fold-line 37. Extending from each of the tapered portions 35, 36 is a member 38 having a fold-line indicated at 39 so as to form a flap 40.

The elements 26, 30 and 34 are assembled to form the continuous extractor loop 25 in the following manner:

The portion 27 is placed in superimposed relation with respect to flanges 32 and 33, the apex of the triangular-shaped portion 31 extending through the slit 29. The flaps 28 are then folded over flanges 32, 33 so as to lie flat against said flanges 32 and 33, as best seen in Figure 10. The member 38 is then inserted through the triangular-shaped portion 31 and the flap 40 is folded over so as to lie flat against the base 31' of the triangular-shaped portion 31. Flaps 28 and 40 may then be secured to the flanges 32, 33 and the base portion 31', respectively, by mucilage or other suitable means.

The two oppositely disposed flange-like constructions formed by portions 27 and flanges 32, 33 are adapted to be slidably mounted within longitudinal grooves or channels so as to guide the extractor loop 25 for movement in a rectilinear path, as will be described herein below. As best shown in Figures 4, 6 and 7, the front and rear wall portions 16, 17 of the envelope are each provided at their interior surfaces with a pair of spaced strips 50, 51 and 52, 53, respectively. The upper strips 50, 52 of each pair are secured respectively to the wall portions 16, 17 at their upper ends as indicated at 54 and 55 in Figure 6. Similarly, the lower strips 51, 53 of each pair are secured to the respective envelope wall portions at their lower ends as indicated at 56, 57, respectively. The lower longitudinal edges of the upper strips 50, 52 are slightly spaced above the upper longitudinal edges of the lower strips 51 and 53, as best seen at 58 in Figure 4. It will be obvious that the space between strips 50, 51 and the adjacent front wall portion 16 provides a channel or groove extending longitudinally of the envelope. Similarly, strips 52, 53 cooperate with the adjacent rear wall portion 17 to form a channel or groove opposite to and extending parallel with that formed by front wall portion 16 and strips 50, 51.

As best seen in Figure 6, each of the two oppositely disposed flange-line constructions formed by the wide portions 27 and the flanges 32, 33 and also each of the legs of the elongated U-shaped member 26 are slidably mounted within one of the two oppositely disposed channels or grooves formed by the envelope wall portions 16, 17 and the strips 50, 51, 52, 53. The cooperating wall portions and strips thus serve to provide a means for slidably mounting the extractor loop 25 for guided rectilinear movement. The extractor loop 25 is normally disposed within the envelope and extends longitudinally thereof, the

letters or other contents (indicated at C) being disposed within the loop 25.

As best seen in Figure 4, there is provided a string 60 having one end secured to the right-hand edge 61 of the envelope as at 62. The opposite end of the string 60 passes through the loop portion 34 and is secured together as at 63 in Figure 10 so as to form a loop 64 surrounding the relative narrow section 37 of the loop portion 34. It will be noted that when the extractor loop 25 is in its initial position as shown in Figure 4, the string 60 is slack.

At the opposite or left-hand end 69 of the envelope as viewed in Figure 4, there is provided a means in the form of a string 70 for quickly and efficiently opening the end 69 of the envelope. The lower end of the string 70 is secured to the corner of the envelope as at 71 and the string 70 extends interiorly of the envelope and upwardly along the edge formed by the fold-line 21. The upper end 72 of the string 70 projects outwardly from the envelope so as to enable the upper end 72 to be manually gripped. Secured to the left-hand end of the extractor loop 25 is a string 73 for a purpose to be described below.

Operation

The manner of opening the envelope and extracting the contents C therefrom will now be described. Referring particularly to Figures 1, 2, 3, the envelope is first grasped in the manner shown in Figure 1, the operator gripping the projecting end 72 of the tear string 70 and pulling outwardly and downwardly on the string 70 so as to rip open the end 69 of the envelope along the fold-line 21. The operator then grasps the string 73, as shown in Figure 2, and pulls the string outwardly so as to draw the extractor loop 25 through the open end 69 of the envelope. The extractor loop 25 surrounds the contents C and draws the contents C outwardly to the position shown in Figure 3. Referring to Figure 5, it will be noted that at a predetermined outward position of the extractor loop 25 and the contents C, the string 60 will have been drawn taut. Thereupon, continued tension on the string 13 and continued outward movement of the extractor loop 25 causes the loop 64 of the string 60 to tear or sever the relatively weak narrow section 37 of the loop portion 34. It will be obvious that when the weak portion 37 is torn or severed, the extractor loop 25 will no longer be in the form of a continuous loop but will consist merely of two longitudinal strips joined together at only one end, the opening at the torn or severed end enabling the severed extractor loop 25 to be easily removed from the contents C after the loop 25 and contents C have been partially or completely extracted from the envelope.

I claim:

1. In combination with an envelope having front and rear flaps and a detachable end flap, an extractor longitudinally movable in said envelope and including substantially parallel arms connected to form a continuous loop, said arms being positioned wholly within the envelope and substantially coextensive in length therewith and arranged to receive the contents of the envelope between them, means slidably connecting the arms of the extractor to the front and rear flaps, and means for severing the detachable end flap from the envelope so as to expose the arms of the extractor in order that the same may be manually engaged and pulled outwardly to withdraw the contents of the envelope therefrom.

2. In combination with an envelope having front and rear flaps and a detachable end flap, an extractor longitudinally slidable in said envelope and including substantially parallel arms connected at one end, a severable member for temporarily connecting the opposite ends of said arms together, flexible means connecting the severable member to the envelope and arranged when the ejector is moved outwardly beyond a predetermined distance to separate the severable member into sections and disconnect the ends of the arms from each other, said arms being positioned wholly within the envelope and arranged to receive between them the contents of the envelope, guide means slidably connecting the arms of the extractor to the front and rear flaps, and means for severing the detachable end flap so as to expose the adjacent ends of the arms in order that they may be manually engaged and pulled outwardly to remove the contents of the envelope.

3. In combination with an envelope as called for in claim 2 in which said guide means includes longitudinal grooves formed in the front and rear flaps, and said arms having means slidably mounted in said grooves for maintaining the extractor in proper position when moved relative to the envelope.

4. In combination with an envelope having front and rear flaps and a detachable end flap, an extractor longitudinally movable in said envelope and including substantially parallel arms connected to form a continuous loop adapted to enclose the contents of the envelope, said loop being provided at one end with a weakened portion, flexible means connected to said weakened portion and the envelope and arranged when the ejector is moved outwardly beyond a predetermined distance to sever the loop, guide means on

said front and rear flaps for slidably receiving portions of said arms, and means for severing the detachable end of the flap so as to expose the arms of the ejector in order that they may be manually engaged and pulled outwardly to remove the contents of the envelope therefrom.

5. In combination with an envelope having front and rear flaps and a detachable end flap, an extractor longitudinally movable in said envelope and including a substantially U-shaped member having parallel arms terminating in laterally extending portions, a weakened strip connected to said arms, the contents of said envelope arranged to be confined between the arms and said strip, a string connected at one end to said strip and at its other end to the envelope, said string when the ejector is moved outwardly beyond a predetermined distance severing the strip so as to release said arms and allow removal of the contents of the envelope therefrom, longitudinally disposed guide means on said front and rear flaps for slidably receiving the lateral portions of said arms, and means for severing the detachable end flap so as to withdraw the ejector and contents of the envelope and when the ejector is moved outwardly a predetermined distance to sever the weakened strip.

JOSEPH A. RUSSO.
